GUARD PLATE FOR MOWERS

Henry Flohr, Jr., Encampment, Wyo.

Application August 24, 1942, Serial No. 455,929

1 Claim. (Cl. 56—309)

The present invention relates to new and useful improvements in guard plates for the sickle bar of mowers and has for its primary object to provide a self-sharpening guard plate of this character and includes the provision of a wear plate for the rear edge of the reciprocating cutter.

A further object is to provide an attachment of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout and in which:

Figure 1 is a side elevational view showing the guard plate in position with respect to the guard of the mower.

Figure 2 is a bottom plan view of the guard plate, and

Figure 3 is a sectional view taken on a line 3—3 of Figure 1.

Referring now to the drawing in detail wherein for the purpose of illustration I have disclosed a preferred embodiment of the invention, the numeral 5 designates the guard plate generally which includes a tongue 6 at its front end having its upper surface beveled as shown at 7 for conformably fitting in the guard of conventional construction and shown by the dotted lines at 8 in Figure 1 of the drawing.

The undersides of the guard plate adjacent each longitudinal edge thereof are serrated as shown at 9 with the serrations extending at an inclined direction and opposite to each other at the respective opposite side edges of the plate as shown to advantage in Figure 2 of the drawing. The portion of the guard plate having the serrations 9 overlies the reciprocating cutter bar 10 so as to sharpen the edge of the teeth of the cutter bar during the reciprocation thereof.

The intermediate portion of the plate 5 is offset upwardly as shown at 11 in order to clear the rivets 12 employed for securing the blades to the cutter bar.

5 The rear portion of the guard plate 5 is offset downwardly below the plane of the front portion thereof to form a shoulder 13 and the rear portion of the plate is bent upon itself to form a double thickness of material including an upper layer of material 14 and a lower layer of material 15, the lower layer 15 projecting forwardly of the shoulder 13 to accommodate the rear edge of the blade 10.

10 The front edge of the lower layer of material 15 is bent downwardly as shown at 16 to provide a wear plate for the rear edge of the cutter bar.

15 An opening 17 is formed in the double layers of material 14 and 15 to accommodate the attaching bolt 18 employed for securing the guard 8 to the mower.

20 The guard plate is transversely curved as shown in Figure 3 to incline the serrated edges 9 downwardly at each side.

25 It is believed the details of construction, advantages and manner of use of the device will be readily understood from the foregoing without further detailed explanation.

Having described the invention, what is claimed as new is:

30 A guard plate for mowers and comprising integrally formed front and rear sections, said front section being flat and adapted to overlie the moving cutter of the mower and having serrations on its underside arranged in strips adjacent each side edge of the plate, a shallow longitudinally extending groove on the underside of the front section between the strips of serrations to position the strips on a plane below the remainder of said front section of the plate and means for attaching the rear section to the mower.
